DESIGN FOR A LENS PANEL FOR A LIGHTING FIXTURE

William M. Adrian, Evanston, Ill., assignor to Patent License Corporation, Chicago, Ill., a corporation of Illinois

Application December 18, 1944, Serial No. 116,957

Term of patent 14 years

(Cl. D48—16)

To all whom it may concern:

Be it known that I, William M. Adrian, a citizen of the United States, residing at Evanston, in the county of Cook and State of Illinois, have invented a new, original, and ornamental Design for a Lens Panel for Lighting Fixture, of which the following is a specification, reference being had to the accompanying drawing, forming a part thereof.

In the drawing:

Fig. 1 is a front elevational view of a lens panel for lighting fixture, showing my new design;

Fig. 2 is a bottom plan view;

Fig. 3 is an end elevational view; and

Fig. 4 is a fragmentary sectional view on a line corresponding to line 4—4 of Fig. 2.

I claim:

The ornamental design for a lens panel for a lighting fixture, substantially as shown.

WILLIAM M. ADRIAN.
